UNITED STATES PATENT OFFICE

JOSEPH HOWARD SLOCUM, OF LONG BEACH, CALIFORNIA

GAS LIFT PUMP

Application filed July 3, 1929. Serial No. 375,770.

This invention relates to deep well pumps, and particularly to the type of pump known as gas lift, or air lift pumps. In this type of pump, gas or air under high pressure is 5 liberated at a low level in the flow pipe, and this creates an upward flow of the liquid being pumped. It has been a common practice to operate pumps of this type by forcing high pressure gas down the well either in a 10 small pipe or else in an outer casing surrounding an inner flow pipe and permitting this gas to be discharged into the flow pipe at a low level.

With these methods the interior of the well 15 is usually subjected to the high pressure gas, or air, and where the well is of considerable depth, this pressure is high and is objectionable because it tends to force oil out of the sand around the well, which action may sometimes be more beneficial to an adjoining well 20 than to the well in which the gas lift pump is operated. Furthermore, in very deep wells it frequently happens that the last casing employed is of too small diameter to carry the usual two pipes that are employed in ordinary gas lift pumps.

The general object of this invention is to provide a gas lift pump of simple construction 25 which will overcome these difficulties, and which will provide simple means for employing gas without subjecting the oil sands to any pressure; also to provide a construction for the pump which will enable the down-pipe that carries down the gas or air under pressure to be let down the flow pipe and seated after the flow pipe is in position.

A further object of the invention is to construct the down-pipe and the pump so that when the down-pipe is pulled all of the liquid standing in the flow pipe will be released. This avoids what oil drillers call a "wet pulling job"; in other words, it avoids drawing pipe from the well that is carrying oil in it.

A further object of the invention is to 45 provide simple means for effecting a proper seating of the lower end of the down-pipe at the point where the high pressure gas or air is discharged, and also to provide simple means for entraining the pumped liquid and for regulating the entraining effect.

A further object of the invention is to improve the general construction of pumps of this type.

Further objects of the invention will appear hereinafter.

It should be stated that this pump can be operated with high pressure air or high pressure gas. It is preferable, however, to operate it with high pressure dry gas, which will return to the mouth of the well of course as 60 wet gas.

According to this invention, the down-pipe may be passed down the flow pipe and properly seated. In the operation of the pump the high pressure gas passing down the down-pipe is delivered through a nozzle which discharges the high pressure gas upwardly in the flow pipe and means cooperate with this nozzle to entrain the pumped liquid.

The invention consists in the novel parts 70 and combinations of parts to be described hereinafter, all of which contribute to produce an efficient gas lift pump.

A preferred embodiment of the invention is described in the following specification, 75 while the broad scope of the invention is pointed out in the appended claims.

In the drawings:

Figure 1 is a vertical section through a gas lift pump embodying my invention and showing a portion of the flow pipe and down-pipe, the former of which carries the pumped liquid upwardly and the latter of which conducts the high pressure gas downwardly. Figure 1 is a vertical section of the line 1-1 of Figure 2.

Figure 2 is a vertical section through the pump taken about on the line 2-2 of Figure 1.

Figure 3 is a horizontal cross section taken 80 through the pump body on the line 3-3 of Figure 1.

Figure 4 is a horizontal cross section taken 85 on the line 4-4 of Figure 1.

Figure 5 is a horizontal cross section taken 90 on the line 5-5 of Figure 1.

In the preferred embodiment of the invention illustrated in the drawings, the pump comprises a body 1 which is preferably in the form of an elongated casting having means 100

such as screw-threads 2 at its upper end to enable the same to be secured to a section of flow pipe 3. In other words, the upper end of the body has a threaded socket to 5 receive the threaded lower end of a section of the flow pipe. The lower end of the body 1 has an opening 4 which may rest immersed in the liquid in the well or may be threaded as indicated to receive a foot section of flow 10 pipe which is immersed below the liquid level in the well. This opening 4 communicates with a liquid chamber 5 within the body 1. The body is further provided with a high pressure chamber 6 which extends longitudinally 15 within the body, being separated from the liquid chamber 5 by a partition wall or web 7. The high pressure gas is carried down to the body through a down-pipe 8. The down-pipe is received in an inlet 9 formed into the high pressure chamber 6 at the upper end of the body, and this inlet is preferably in the form of a tapered socket eccentric with respect to the axis of the pipe 3, the lower end of the down-pipe 8 being 20 formed with a tapered tip 10 to seat in this socket. Any suitable means may be provided, however, at this point enabling the downwardly moving down-pipe to seat and make a gas tight connection with the inlet 9. 25 The pump also includes a discharge nozzle 11, the lower end of which is screwed into the lower portion of the body 1 so as to receive high pressure gas from the chamber 6 and discharge the same in an upward direction into the flow pipe. In doing this the discharge gas cooperates with suitable entraining means. In the present instance this entraining means is in the form of a Venturi tube 12 which is coaxial with the nozzle and 30 disposed just above it. The discharge nozzle and the Venturi tube are mounted for relative movement in a longitudinal direction. This relative movement enables the cooperative action of the nozzle and the Venturi tube to 35 be regulated. In the present instance the nozzle 11 may be held fixed and the Venturi tube 12 is mounted in a threaded opening 13 in which it can be adjusted up or down by means of screw-driver notches 14 formed in 40 the upper end of the tube. 45 Suitable means is provided for guiding the down-pipe 8 when it is lowered and arrives at the pump body, to center it and direct it into the tapered inlet 9. Any suitable means 50 may be employed for this purpose. In the present instance I provided two guide springs 55 60 in the form of leaf springs of bow-form secured by fastening means 16 at their upper ends to the inside of the flow pipe 3. The bowed sides of these springs engage the down-pipe as it comes down and hold it in line with inlet 9.

The parts described above will operate effectively to develop an upward flow of the 65 pumped liquid in the flow pipe. I prefer

to provide means, however, for releasing the liquid in the flow pipe when the down-pipe 8 is pulled. For this purpose I provide a release port located in such a way that when the down-pipe is in position this release port is closed. In the present instance I provide a release port 17 extending outwardly into the well through the body 1 at the tapered inlet 9. With this construction it will be evident that when the down-pipe 8 is pulled, liquid, for example, oil in the flow pipe, can flow back through the nozzle and out through the opening 17 into the well. 70 75

It will be evident that in the operation of this pump the oil sand is not subjected to any pressure. On the other hand, it is subjected to a suction effect or partial vacuum that is created in the liquid chamber 5 through the entraining action of the discharge nozzle 11. This is advantageous and tends to increase 80 85 the production of the oil from the local sands around the well.

While this suction effect is being developed in the chamber 5 it will be evident that where high pressure gas is employed a very effective upward flow of the liberated gas will take place in the flow pipe enabling this pump to operate effectively even with the deepest wells used in practice. 90

It is understood that the embodiment of the invention described herein is only one of the many embodiments this invention may take, and I do not wish to be limited in the practice of the invention, nor in the claims, to the particular embodiment set forth. 95 100

What I claim is:

1. In a gas lift pump for deep wells, the combination of a pump body having a high pressure chamber formed therein for receiving the high pressure gas and having an inlet on the upper side of the body, said inlet having an eccentric tapered socket, a down-pipe extending down from the mouth of the well for leading the high pressure gas down to the pump body, and having a tapered tip at its lower end capable of seating in the said socket, a flow pipe enveloping the down-pipe and attached to the body and located so that the down-pipe lies adjacent to its side wall, a nozzle communicating with the said high pressure chamber for delivering the high pressure gas or air into the lower end of the flow pipe, and means associated with the nozzle for entraining the pumped liquid. 105 110 115

2. In a gas lift pump for deep wells, the combination of a pump body having a high pressure chamber formed therein for receiving the high pressure gas and having an inlet on the upper side of the body, said inlet having a tapered socket, a down-pipe extending down from the mouth of the well for leading the high pressure gas down to the pump body, and having a tapered tip at its lower end capable of seating in the said socket, a flow pipe enveloping the down-pipe and at- 120 125 130

tached to the body, a nozzle communicating with the said high pressure chamber for delivering the high pressure gas or air into the lower end of the flow pipe, means associated with the nozzle for entraining the pumped liquid, and a release port leading out to the well adjacent the tapered socket in a position to be closed by the down-pipe, and operating when the down-pipe is pulled to release the oil standing in the flow pipe back into the well.

3. In a gas lift pump having a flow pipe, a pump body having a chamber for receiving the high pressure gas, said chamber having an inlet on the upper side of the body in the form of an eccentric tapered socket, said body having means on its upper side for attaching the same to the lower end of the flow pipe, a nozzle within the body communicating with the said chamber discharging into the flow pipe, and means cooperating with the nozzle for entraining the liquid to be pumped.

4. In a gas lift pump having a flow pipe, a pump body having a chamber for receiving the high pressure gas, said chamber having an inlet on the upper side of the body in the form of a tapered socket, said body having means on its upper side for attaching the same to the lower end of the flow pipe, a nozzle within the body communicating with the said chamber discharging into the flow pipe, and means cooperating with the nozzle for entraining the liquid to be pumped, said tapered socket operating to receive the lower end of the down-pipe delivering high pressure gas to the pump body, and having a release port in the wall thereof for releasing the oil from the flow pipe when the down pipe is pulled.

5. In a gas lift pump, the combination of a pump body having a high pressure chamber formed therein and having an inlet opening into said chamber on the upper side of the body, a down-pipe extending down from the mouth of the well, said inlet and said down-pipe being constructed so as to be capable of forming a tight connection by the downward shifting movement without rotation of the down-pipe, into the inlet opening, a flow pipe attached to the upper end of the body and enveloping the down-pipe, means for guiding the down-pipe adjacent the body to align the same with the said inlet opening when it is being seated, means for discharging the high pressure gas from the high pressure chamber into the flow pipe, and means associated therewith for entraining the pumped liquid.

6. In a gas lift pump, the combination of a flow pipe, a pump body connected at its upper end to the flow pipe, said pump body having a high pressure chamber therein with an inlet on the upper side of the body, a down-pipe within the flow pipe, said inlet

and said down-pipe having means enabling the down-pipe to be seated and form a tight connection with the inlet by the relative downward shifting movement without rotation of the down-pipe in the flow pipe, means located at the lower end of the flow pipe for guiding the down-pipe into the inlet, means for discharging the high-pressure gas upwardly in the flow pipe, and means associated therewith for entraining the pumped liquid.

7. In a gas lift pump for deep wells, the combination of a flow pipe, an eccentric down-pipe extending down the flow pipe with means for seating the lower end of the same in the flow pipe, a discharge nozzle connected with the down-pipe and located on the other side of the axis of the flow pipe, from the down-pipe for developing an upward flow in the flow pipe, and means associated therewith for entraining the pumped liquid.

8. In a gas lift pump for deep wells, the combination of a flow pipe, an eccentric down-pipe extending down the flow pipe with means for seating the lower end of the same in the flow pipe, a discharge nozzle connected with the down-pipe and located on the other side of the axis of the flow pipe, from the down-pipe for developing an upward flow in the flow pipe, and a Venturi tube located within the flow pipe cooperating with the nozzle for entraining the pumped liquid.

9. In a gas lift pump for deep wells, the combination of a flow pipe, a pump body carried thereby, an eccentric down-pipe extending down the flow pipe with means for seating the lower end of the same at its lower end in the body, a discharge nozzle mounted in the body, connected with the down-pipe and located on the other side of the axis of the flow pipe, from the down-pipe for developing an upward flow in the flow pipe, and a Venturi tube located within the body cooperating with the nozzle for entraining the pumped liquid, said Venturi tube and said nozzle being relatively movable longitudinally to regulate their cooperative action.

10. In a gas lift pump for deep wells, the combination of a flow pipe, a pump body attached to the lower end of the flow pipe, said pump body having a high pressure chamber for receiving the high pressure gas, said high pressure chamber having a tapered inlet on the upper side, a down pipe extending down from the mouth of the well for leading the high pressure gas down to the pump body and having a tapered tip at its lower end capable of seating in the tapered inlet, said body having a nozzle communicating with said chamber and projecting upwardly for discharging the gas upwardly into the flow pipe, and a Venturi tube mounted in the body above the nozzle and cooperating with the

nozzle to entrain the pumped liquid and carry the same up the flow pipe.

11. In a gas lift pump for deep wells, the combination of a flow pipe, a pump body attached to the lower end of the flow pipe, said pump body having a high pressure chamber for receiving the high pressure gas, said high pressure chamber having a tapered inlet on the upper side, a down pipe extending down from the mouth of the well for leading the high pressure gas down to the pump body and having a tapered tip at its lower end capable of seating in the tapered inlet, said body having a nozzle communicating with said chamber and projecting upwardly for discharging the gas upwardly in the flow pipe, a Venturi tube mounted in the body above the nozzle and cooperating with the nozzle to entrain the pumped liquid and carry the same up the flow pipe, and resilient guiding means for guiding the down pipe when the same is let down the flow pipe to center the same and seat its tapered tip in the tapered inlet.
12. In a gas lift pump for deep wells, a pump body having means at its upper end for attaching the same to a flow pipe, and having a high pressure chamber within the same with an inlet at the upper end of the body, said body having a liquid chamber therein with means for admitting liquid thereto at the lower end of the body, a discharge nozzle mounted in the body within the liquid chamber and receiving gas from the high pressure chamber, and a Venturi tube mounted in the upper end of the body and cooperating with the nozzle to entrain liquid from the liquid chamber and force the same up the flow pipe.

40 Signed at Los Angeles, Calif., this 24th day of June, 1929.
JOSEPH HOWARD SLOCUM.
